TABLE OR THE LIKE

Herbert Ritts, P.O. Box 64336, Los Angeles, Calif.

Filed Jan. 21, 1963, Ser. No. 73,265

Term of patent 7 years

(Cl. D33—14)

Fig. 1

Fig. 2

Fig. 3

The sides not shown are substantially the same in appearance as the side shown in FIGURE 2.

I claim:

The ornamental design for a table or the like, substantially as shown.
